UNITED STATES PATENT OFFICE.

WALTER E. PIPER, OF SUDBURY, MASSACHUSETTS.

OVERSHOE.

Application filed March 12, 1926, Serial No. 94,295.

My present invention is directed to an improved overshoe or "arctic" equipped with a closure or fastener of the metallic type, originally illustrated by the Judson Patents 5 504,037 and 504,038, and more recently improved and developed by numerous modifications of which the G. E. Prentice Patent 1,562,254, dated November 17, 1925, is typical.

10 In the manufacture of overshoes, wherein metallic fasteners of the above type are utilized, as heretofore universally made, the design and construction of the entire shoe is for the application of the fastener at the 15 front center line of the overshoe from the forepart up over the instep. This arrangement has resulted in considerable difficulty, since the fasteners of the metallic type, as above noted, with interlocking portions, necessarily 20 necessitate a delicate and relatively fine action of the interlocking members to permit the action of the slide in opening or closing the devices, and do not operate efficiently over such a curved surface as at the instep of the 25 shoe. This difficulty, however, has been somewhat overcome by attaching the metallic strips and interlocking members to yielding devices, but a further and great difficulty has been that the constant flexing and 30 bending of the entire overshoe and the attached metallic fasteners, during walking, results in distorting the metallic members, throwing the interlocking portions out of alignment, and even breaking the parts. It 35 will be appreciated that constant bending, to and fro, of the small, light metallic members, particularly where wire-like interlocking devices are employed, as in the Prentice patent above noted, necessarily results in 40 weakening the wire and a continuous bending quickly tends to break the same. A further objection to the use of these metallic fasteners along the front part of the overshoe, particularly for ladies' wear, and when 45 worn over leather shoes, pumps, slippers, etc., is the undue stiffness and resistance to the bending and flexing of the ankle of the wearer.

I have discovered that there is a substantially non-flexing portion of an overshoe, or

at least so slightly bent and flexed, that no injury will result to a metallic fastener positioned along this line of relatively slight distortion during walking. Thus I have found that by positioning a metallic fastener of 55 the type above noted, along the side of the overshoe and practically in a line free from substantial bending, that the metallic fastening devices are maintained in efficiency, preserved from distortion, prevented from 60 jamming, or becoming unworkable, and preserved from breaking the interlocking parts. Such a line, I find, is along either side of the overshoe, substantially midway between the instep line and heel portion, but preferably inclined, rather than in a vertical position. While such a positioning of the metallic fastener may be on either the right or left sides of the overshoe, I prefer to 65 position the fastener on the right side of a left overshoe, known as the "inside" and on the left side of a right overshoe. This gives slightly less distortion, enables the wearer to more conveniently fasten or unfasten the device and preserves the overshoe material 70 intact on the outer or more readily visible surface.

A further advantage, which I find in my present invention, is that the entire shoe structure, pattern and article, may be more 75 accurately made, cut and fitted, with a smooth uncut surface along the front, over the instep, having the closure and attached metallic fastener at the side and substantially along the line of least distortion imparted 80 to the shoe during walking.

Thus, in carrying out my present invention I first make and form the shoe substantially along the lines of the pattern therefor, as shown in my copending application, 85 Ser. No. 96,766, filed March 23, 1926, with the closure opening positioned slightly inclined or diagonally from the lower part upwardly and rearwardly, although I can, of course, make the closure in a substantially 90 vertical position with regard to the tread surface of the overshoe. In either position, the metallic fasteners are applied in a practically straight line, and are maintained in this position, with slight distortion 95 100

during walking, thus preserving the metallic fastenings in their necessarily fine interlocking adjustment, insuring the quick and easy operation of the fastening and unfastening 5 guide block, and preserving the metallic members in most efficient operation, while actually improving the fitting, appearance and construction of the shoe, by having the upper materials extend smoothly over the 10 instep.

I am aware that heretofore leather shoes have been made with fastenings on the side, but these have been either eyelets and lacing, buttons and button holes, or elastic webbing—but no such difficulty or problem is 15 presented with such prior fastenings as is present with a metallic fastener of the Judson or Prentice type. Such prior devices, also have usually been applied to 20 leather shoes, which, ordinarily, do not extend as high upon the leg of the wearer as do overshoes, and which leather shoes do not require to be so quickly and easily applied, fastened, unfastened and removed, as 25 do overshoes. Furthermore, there was no necessity in prior devices, of having the fastening elements positioned along a substantially non-flexing line, and prior to my present invention, it has not been thought possible—so far as I am aware—to apply a 30 metallic fastening to any other part of an overshoe than directly along the front medial line. I believe that I am the first to have discovered the desirability of positioning a metallic interlocking fastener 35 along the side of an overshoe, and the first also, to have discovered a substantially non-flexing line along which such a metallic fastener can be applied in an overshoe and 40 therefore I claim the same herein broadly.

Referring to the drawings illustrating a preferred embodiment of my invention,

Fig. 1 is a front view of my improved overshoe;

Fig. 2 is a side view showing the fastener in a preferred position on a diagonal alignment at the left side of a right shoe.

In applying my invention, any size, shape or style of overshoe may be employed, wherein the sole 1, heel 2, and side part 3 may be and are of usual interlaced rubber and textile material, the upper comprising substantially waterproofed textile material 5, fitted snugly over the instep portion 6 and with the opening to receive the closure along the lines substantially as shown at 7 and 8 on the "inside" portion of each overshoe. An inner pocket 9 is applied as usual. To the edges 7 and 8 are secured the 10 opposite rows of interlocking metallic fastening members designated generally at 10 and operated by a sliding guide block 12 moved by a handle 14, which guide block—as is usual and well known in all these types of 15 metallic fasteners, serves to position, inter-

lock and fasten the opposite parts of the metallic fastener when being drawn from bottom to top—or vice versa—with the closure open, while serving equally to unlock the interlocking parts when moved from top to bottom—or vice versa—to open the overshoe. If desired the usual protecting flap 15 is applied to enclose and protect the top part 20 of the fastener secured in position by a socket 16 and stud 17 or by buckle or other 25 desired device.

With the metallic fastener secured to the opposite edges of the closure, as indicated at 7 and 8, and substantially along a slightly diagonal line from a position preferably 30 over the arch of the foot, up to a point practically midway of the forward and rearward portions of the top of the overshoe, I 35 secure the advantages of having the entire metallic fastener and the interlocking parts, when closed in practically a non-movable or non-distorting line, during the necessary flexing of the overshoe while the wearer is walking. This position is so slightly flexed 40 or distorted as to be a non-injurious movement, or a distortion so slight as to be normally taken up by the necessary looseness in the parts and not requiring a damaging distortion or bending of the metallic members. Furthermore I secure a better, easier 45 and smoother fitting over the instep. Thus I am enabled to produce an improved overshoe, with lasting qualities and yet embodying the advantages of a smooth front portion and a metallic fastener. The ordinary flexing or bending required in the position where I have placed the fastener is usually taken up by the flexibility of the cloth itself, and thus—in effect—frees the 50 metallic fastener and interlocking members substantially, if not entirely, from any damaging strain or displacement. Furthermore, 55 the appearance of the entire overshoe is improved, and the positioning of the metallic or automatic fastener substantially out of 60 view, is a highly advantageous feature.

My invention is further described and defined in the form of claims as follows:

1. An improved overshoe having a smooth unbroken surface over the instep and front portion, a closure opening positioned on a diagonal line extending from a point over the forward part of the arch of the overshoe up to a point substantially midway of the front and rear portions of the top of the overshoe and along the inner side portion thereof, and an interlocking metallic slide fastener secured along the sides of said opening, said opening and fastener being thus positioned in a line substantially free from 110 distorting action during walking.

2. That improvement in the art of manufacturing rubber overshoes, which consists in making the upper with a smooth, unbroken surface over the instep and front 115

portion, and positioning an interlocking metallic slide fastener along the inner side portion of the upper on a diagonal line extending from a point over the forward part of the arch of the overshoe up to a point substantially midway of the front and rear portions of the top of the overshoe and in such

a position that the flexing of the shoe during walking will be without a breaking strain on the interlocking metallic portions 10 of the fastener.

In testimony whereof, I have signed my name to this specification.

WALTER E. PIPER.
